Primary Examiner — Marissa J Cash*Assistant Examiner* — Kayla Marie Bennett(74) *Attorney, Agent, or Firm* — Kunzler Bean & Adamson, PC; Michael Bartholomew(57) **CLAIM**

The ornamental design for an impact electric drill, as shown and described.

DESCRIPTION

FIG. 1 is a front, right and top perspective view of an impact electric drill, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of portion 9 shown in FIG. 1. The broken lines in the drawings depict portions of the impact electric drill that form no part of the claimed design. The dot-dash-dot broken lines encircling the enlarged views in FIGS. 1 and 9 are for annotative purposes only and form no part of the claim thereof.
